[57] CLAIM

The ornamental design for a slide fastener presser foot, substantially as shown.

DESCRIPTION

FIG. 1 is an isometric view taken from above and looking towards the front and one side of a slide fastener presser foot showing my new design;

FIG. 2 is a top plan view of the slide fastener presser foot;

FIG. 3 is a side elevational view of the slide fastener presser foot, as seen from the left of FIG. 1;

FIG. 4 is a front elevational view of the slide fastener presser foot;

FIG. 5 is a rear elevational view of the slide fastener presser foot of FIG. 2; and

FIG. 6 is a bottom plan view of the slide fastener presser foot.
